UNITED STATES PATENT OFFICE.

PETER FRANTZ, OF STERLING, ILLINOIS, ASSIGNOR TO FRANTZ MANUFACTURING CO.,
OF STERLING, ILLINOIS, A CORPORATION OF ILLINOIS.

TRACK FOR DOOR-HANGERS.

REISSUED

993,161.

Specification of Letters Patent.

Patented May 23, 1911.

Application filed January 13, 1911. Serial No. 602,430.

To all whom it may concern:

Be it known that I, PETER FRANTZ, a citizen of the United States of America, and a resident of Sterling, in the county of White-
5 side and State of Illinois, have invented cer-
tain new and useful Improvements in Tracks
for Door-Hangers, of which the following is
a specification.

This invention relates to that type of
10 overhead tracks for sliding doors, in which
an extended horizontal wrought metal shell
having an inturned or lateral flange at its
lower edge provides a track for the usual
tandem wheels of the hanger. And the
15 present improvement has for its object to
provide a simple and efficient structural
formation and combination of parts whereby
strength to resist flexure of the track with
lightness and economy of material is at-
20 tained, and with which standard lengths of
the track can be coupled together in a ready
and effective manner to provide a track of
any desired extent, all as will hereinafter
more fully appear.

25 In the accompanying drawings:—Figure
1, is a detail front elevation of a track em-
bodying the present invention, and illustrating
the coupling between standard lengths
30 of the track. Fig. 2, is a transverse section
on line $x-x$, Fig. 1. Fig. 3, is a similar
view of a modification.

Similar numerals of reference indicate
like parts in the different views.

Referring to the drawings, 1 represents
35 portions of two adjoining lengths of the
track coupled together by a coupling band
or member 2 hereinafter described in detail.
In the present construction each length of
40 track comprises an upper vertical attaching
web 3, from the lower end of which extends
outwardly an inclined shed portion or web 4,
and from the outer end of said shed depends
a vertical web 5, the lower end of which
45 terminates in an inturned and preferably
trough shaped web 6 which constitutes the
longitudinal track for the usual tandem
wheels of a door hanger, and said vertical
web 5 also terminates in an outwardly ex-
50 tending inclined web 7, which is adapted to
very efficiently brace and support the track
against ordinary stress in actual use. It is
within the province of this part of the pres-
ent invention to make the inclined bracing
55 web 7 integral with the other webs 3, 4 and
5, and secure the web 6 thereto as a separate

part, as illustrated in Fig. 2, or to make the
webs, 3, 4, 5 and 6 integral, and secure the
web 7 thereto as a separate part, as illus-
trated in Fig. 3.

The coupling band 2 above referred to is 60
formed from a flat bar of metal bent to the
outer contour of the webs 3, 4, 5 and 7 above
described, and adapted to closely fit the
outer surface of the same, as shown in Figs.
2 and 3.

65 8 is a screw passing through the upper end
of the coupling band 2, to effect an attach-
ment of the track to the face of a wall or
the like.

70 9 is an angle bracket arranged in the in-
terior of the track and provided with a
vertical member adapted to bear against the
wall, and an inclined top member that rests
beneath and supports the inclined shed por-
tion or web 4 of the track. Said bracket is 75
secured to the coupling band 2 in spaced re-
lation corresponding to the thickness of the
web 4, by rivets 10 and interposed washers
or collars 11, as shown.

75 12 is a supporting bracket arranged under-
neath the track and formed with an inclined
upper arm which rests beneath and supports
the web 6, and with a lower inclined arm
that is secured to an adjacent portion of the
coupling band 2, in spaced relation corre-
80 sponding to the thickness of the web 7, by
rivets 13 and interposed washers or collars
14 as shown.

85 With the described arrangement of the
coupling band 2, and brackets 9 and 12, 90
sockets are provided for the reception of the
adjoining ends of track lengths, and in my
preferred construction, as shown in Fig. 1,
the webs 3, 4, 5 and 7 are separated a dis-
tance equal to the diameter of the attaching
95 screw 8, or washers 11 and 14, while the web
6, which constitutes the track surface, pro-
jects beyond the other webs to abut against
the next adjacent web 6, and provide a con-
tinuous track surface.

100 Having thus fully described my said in-
vention what I claim as new and desire to
secure by Letters Patent, is:—

1. A track member formed with an upper
vertical web, an inclined web extending out-
wardly from the lower end of said vertical
web, an intermediate vertical web depending
from the outer end of said inclined web, an
inturned web extending laterally from the
lower end of said intermediate web, and an 110

outwardly inclined web depending from the lower end of said intermediate vertical web, substantially as set forth.

2. A track comprising in combination a pair of track lengths each formed with an upper vertical web, an inclined web extending outwardly from the lower end of said vertical web, an intermediate vertical web depending from the outer end of said inclined web, an inturned web extending laterally from the lower end of said intermediate vertical web and an outwardly inclined web depending from the lower end of said inter-

mediate vertical web, a coupling band formed to fit the exterior of the track 15 lengths, and supporting brackets secured in separated relation to said coupling band to form receiving sockets for the end of the track lengths, substantially as set forth.

Signed at Chicago, Illinois this 11th day 20 of January 1911.

PETER FRANTZ.
